UNITED STATES PATENT OFFICE

JAMES H. RAND, JR., AND JOHN A. ZELLERS, OF BUFFALO, NEW YORK, ASSIGNORS TO
REMINGTON RAND INC., OF NEW YORK, N. Y., A CORPORATION OF DELAWARE

DESIGN FOR A FRAME FOR TYPEWRITING MACHINES

Application filed December 29, 1932. Serial No. 46,655. Term of patent 3½ years.

To all whom it may concern:

Be it known that we, JAMES H. RAND, JR., and JOHN A. ZELLERS, citizens of the United States, residing at Buffalo, in the county of Erie and State of New York, have jointly invented a new, original, and ornamental Design for a Frame for Typewriting Machines, of which the following is a specification, reference being had to the accompanying drawings, forming a part thereof.

Fig. 1 is a perspective view of a frame of

a typewriting machine showing our design.
Fig. 2 is a top plan view of the same.
Fig. 3 is a side elevation of the frame.
We claim:

The original design for a frame for typewriting machines, as shown.

Signed at Buffalo, in the county of Erie and State of New York, this 19 day of Dec., 1932.

JAMES H. RAND, JR.
JOHN A. ZELLERS.
